US00D757766S

(12) **United States Design Patent**
Moon et al.

(10) **Patent No.:** **US D757,766 S**
(45) **Date of Patent:** **** May 31, 2016**

(54) **DISPLAY SCREEN OR PORTION THEREOF
WITH GRAPHICAL USER INTERFACE**

(71) Applicant: **SAMSUNG ELECTRONICS CO., LTD.**, Suwon-si (KR)

(72) Inventors: **Jihyun Moon**, Seoul (KR); **Yongman Park**, Yongin-si (KR)

(73) Assignee: **SAMSUNG ELECTRONICS CO., LTD.**, Suwon-Si, Gyeonggi-Do (KR)

(**) Term: **14 Years**

(21) Appl. No.: **29/479,635**

(22) Filed: **Jan. 17, 2014**

(30) **Foreign Application Priority Data**

Jul. 3, 2013 (KR) 30-2013-0034230

(51) **LOC (10) Cl.** **14-04**

(52) **U.S. Cl.**

USPC **D14/486**

(58) **Field of Classification Search**

USPC D14/485-495

CPC G06F 3/048; G06F 3/0482

CLAIM

The ornamental design for a display screen or portion thereof with graphical user interface, as shown and described.

DESCRIPTION

FIGURE is a front view of a display screen or portion thereof with graphical user interface showing our new design. The large broken lines shown in the drawings illustrate the display screen and the small broken lines illustrate portions of the graphical user interface. All broken lines form no part of the claimed design.
